UNITED STATES PATENT OFFICE.

JOHN F. SCHENCK, SR., OF LAWNDALE, NORTH CAROLINA.

HANK-FORMING MACHINE.

Application filed February 25, 1928. Serial No. 256,992.

This invention relates to improvements in hank-forming machines, one object of the invention being the provision of a machine which will form cordage or rope into hank 5 form in a rapid and thorough manner, and in which from one to any number of hanks may be formed simultaneously.

Another object of this invention is the provision of a machine of this character in which 10 there is provided mechanism whereby the loops are formed, the loop-forming members being held in stationary position while the threading or feeding mechanism is rotated, there being means provided automatically 15 for slowing down the speed of the latter mechanism and rotating the loop holders or supports so that the necessary coils or spirals may be wound thereon to complete the hank, there being automatic means for stopping 20 the machine at the completion of the hank.

Another object of this invention is the provision of a machine of this character which, after being initially started, moves through a sequence of operations automatically up to 25 and including the completion of the coils, the same being so constructed that after a pre-determined number of loops have been placed upon the loop-forming and receiving member, the feeding mechanism is slowed down 30 and the forming mechanism is rotated to receive the coils.

In the accompanying drawings:—

Figure 1 is a plan view, more or less in diagram, of the complete mechanism, only one 35 hank-forming mechanism, however, being shown.

Figure 2 is a view in side elevation showing the mechanism for oscillating the thread-feeding or directing mechanism during the 40 loop-forming operation, the same being in its innermost position.

Figure 3 is a similar view showing the mechanism in the position it assumes when feeding the thread for forming the spirals.

Figure 4 is a view, partly in elevation and partly in section, of the feeding mechanism, the dotted lines illustrating the innermost position thereof.

Figure 5 is an enlarged view in side elevation of the thread or cord guiding spindle and the carrying portion therefor.

Figure 6 is a front elevation of the same showing the parts in the position when locked.

Figure 7 is a view in plan showing the 55 thread or cord feeding mechanism and the operating cam therefor, the dotted lines illustrating the various positions of the spindle throughout the rotation thereof.

Figure 8 is a perspective view of the spin- 60 dle guide.

Figure 9 is a diagram showing several of the first steps in forming the loop.

Figure 10 is a similar view showing the initial starting in forming the spirals. 65

Figure 11 is a perspective view of the completed hank.

In describing the present mechanism, the same will be covered under the following topics: first, mechanism for forming the 70 loops; second, mechanism for shifting at the end of the loop-forming and the operation of the coil-forming mechanism; third, mechanism for forming spirals or coils around the loops; and fourth, the operation of the complete machine. 75

Mechanism for forming loops.

Referring to the drawings, the numeral 10 designates the drive shaft which is driven by 80 the prime mover 11, here shown as a belt and pulley driven mechanism, and it is understood that the same may be any type of prime mover, as, for instance, an electric motor. The drive shaft 10 is mounted in bearings 85 10' and upon this shaft are carried the respective drive pulleys 12, 25 and 46, which, in turn, operate the respective belts 13, 26 and 47. The belt 13, as will presently appear, drives primarily the shaft 15, the belt 26 drives the shaft 28 and the belt 47 drives the shaft 49, which constitute the main driven elements of the present mechanism. 90

The loop-forming mechanism includes primarily the belt 13 which operates through the fixed and loose pulley 14 and 14' the shaft 15, the belt shifter comprising the shaft 16 carrying the shifting member 17 and its operated arm 18 being disposed and operated, as will presently appear, to cause the belt to be moved to connect the pulley 14 with the belt and, consequently, to drive the shaft 15. This shaft, as illustrated, is disposed longitudinally of the machine and is journaled in bearings 19, and has fast thereto a gear 20 which, in turn, meshes with a gear 21 to drive the angularly disposed shaft 22 journaled in bearings 22'. This shaft has a spur gear 23 which is in 100

mesh at all times with the wide spur gear 24 journaled in bearings 24' and which, in turn, drives the gear 66 upon the shaft 67, as will presently appear. At the same time that this shaft is rotated, the shaft 28 is also rotated through the belt 26 and its fast and loose pulleys 27 and 27', the shaft 28 being mounted in journals 29 and carrying the cone pulley 30 which drives the belt 31 and the cone pulley 32 carried by the shaft 33 and mounted in the journals 34. This shaft carries a spur gear 35 which meshes with the large speed-reducing gear 36. This gear is mounted upon a short shaft 37 journaled in bearings 38 and itself carrying a spur gear 39 which meshes with the loose gear 40 mounted rotatably upon the shaft 15, but provided with a ratchet wheel 41, and fast to the shaft 15 is an arm 42 which carries a pin 43, which, in turn, has mounted thereon a spring-actuated ratchet 45 which rides upon the ratchet wheel 41. Inasmuch as the arm 42 is rotated at a relatively rapid speed when the belt 13 is in action, the same rides around without imparting motion to or receiving motion from the gear 40, as the slow speed mechanism operated by the belt 31 will not interfere with the high speed mechanism operated directly through the belt 13, the mechanism driven by belt 31 being operated, as will presently appear, so as to rotate the shafts 15 and 22 at a slower rate of speed than the belt 13 imparted thereto.

The pulley 46, as before stated, operates the belt 47 which, in turn, operates the pulley 48 carrying the male member 48' of the clutch, the same being freely rotatable upon the driven shaft 49 journaled in the bearings 50, the outer member 51 of the clutch being splined upon the shaft 49 for coactive relation with the member 48', the spring 52 thereof normally holding the same in engagement, and the purpose of which will presently appear.

Gears 53 and 54 are carried by the shaft 49 and mesh, as illustrated, with spur gears 51 and 55, the gear 55 being fast upon the shaft 56 journaled in bearings 57, 58 and 58' and carrying the hand-actuated drum 59 upon one end and the loop-receiving and forming hook 60.

The gear 61 is mounted upon the shaft 62 journaled in the bearings 63, and, in turn, carries the fixed associated hook 64 having the adjustable hook 65 whereby the last loop formed is shortened and at a point at the beginning of the starting of the coils or spirals, as will presently appear. The hooks 60 and 64 constitute the main supports for the loops both during their forming and the winding of the coils or spirals thereon.

As before stated, the gear 66 rotates the shaft 67, which is journaled in the pedestal 68, and this pedestal 68 supports the main mechanism of the present device in that the mechanism carried thereby provides for the

feeding of the rope or cordage to form the loops and the spirals of the completed hank, and, as shown in Figure 1, is merely diagrammatic of the structure shown fully and clearly in Figures 4, 5, 6 and 7.

The shaft 67 has rotary as well as longitudinal sliding movement imparted thereto, the spool 69 being mounted thereon and being operated, as will presently appear, to impart the sliding movement to the shaft, and also the feeding arm or member 70 which, as will presently appear, is correlated with the cam 71, so that the spindle 72 may be properly operated to direct the thread to the revolving loop and spiral-forming mechanism.

As shown in Figures 4, 5, 6 and 7, the member 70 is provided with a weighted end 70' and with a case-forming end 70'', the opposite walls of which at the outer end are provided with the inclined slots 70''' and also has slidably mounted therein the longitudinally movable plate *d* which carries the tubular member 70^b for the reception of the spindle or thread-guiding member 72, whose oppositely disposed pins 72^a are mounted in the grooves 70''', so that the member 72 will move at right angles to its carrying member 70 during the slow rotation of the member 70 in its small orbit as it forms the one-half loop around the hook 65 and during the succeeding formation of the spiral.

In forming the loops it is desired to rotate the member 70 at the highest rate of speed, so that the cord or rope *A* taken from the cone *C* through the hollow shaft 67 and guided by the respective guides *e* and *f* may be free to move or slide and thus form, as shown in Figure 9, the loops *L*.

After a sufficient number of these loops have been formed by means of a predetermined number of rapid revolutions of the shaft 15, the mechanism operated and controlled by the properly selected change gear 114, checks the high speed of the shaft 15 by causing the belt 13 to be shifted to the loose pulley 14; and this permits the slow speed mechanism consisting of the belts 26 and 31 to rotate the shaft 15. Closely following this action, the hooks 60, 64 and 65 are rotated, this being started through the instrumentality of the sliding rod 73 which is journaled in the bearings 74 and is provided with the adjusting device 75 and the spring 76, which normally holds the bell-crank lever 77 with its catch 78 in engagement with one free end, as at 80', of the clutch-actuating lever 80.

Thus, when the rod 73 is pulled upon by the pin 79, the catch 77 is released and the spring 52 is free to throw the clutch member 51 into engagement with the clutch member 48' and thus cause the belt 47 to transmit motion to the shaft 49 and the loop-holding and forming hooks 60, 64 and 65, so that the spirals, as will presently appear, will be formed.

The mechanism for changing from high

speed to low speed in the shaft 15 consists, as before stated, of the change gear 114, which drives the short shaft 115 journaled in bearings 115' and carrying thereon a disk 116 with a pin 117 which operates the weighted or pendant lever 118 at the proper time to engage the free end of the lever 119, which, in turn, is provided with a notch 120 for engaging the fixed catch 121 to normally hold the sliding rod 91 to the left, as viewed in Figure 1, and against the tension of its spring 96, and its adjusting member 95. When this was done, the rod 91 was freed to the action of the spring 96 to move from the position as shown in Figure 1 to the right, so that the pin 92 engaged the shifting lever or arm 18 and, in turn, slid the shaft 16 to the right, so that the belt shifter 17 placed the belt 13 from the fixed or fast pulley 14 to the loose pulley 14'.

Going back a little in the operation of the present invention, the shaft 86, which is journaled in bearings 9 is operated by a handle 87 and through the respective pins 88, 89 and 90 operates the respective shifting rods 91, 85 and 100 when the crank is operated to oscillate the shaft 86 to the left at the initial starting of the machine, the pin 88 operating the fork 91' so as to slide the rod 91 against the action of the spring 96 and to cause the weight-actuated latch 119 to have its notch 120 engaged by the finger 121 and thus lock the rod in the position as illustrated. At the same time the shaft 85 through the pin 89 and the lug 97 is moved to the left so that the belt shifter 98 will move the belt 26 from its loose pulley 27' to the fast pulley 27 moving the latch member 110 carried by the rod 85 so as to cause its notch 111 to be engaged by the finger 112 and thus lock the rod 85 against the action of the spring 113. A pin 84 is carried by the rod 85 and is disposed at the proper time to engage the free end 83 of the clutch-actuating lever 80 to throw out the clutch and cause it to be locked by the catch 77, this action taking place at the final spiral-forming operation.

The sliding rod 100 is provided with a forked portion 99 and said rod is slidably mounted in the bearings 101 and is so disposed as to enter a notch 102 of the disk 103 which is fast to the shaft 56, thus aligning the respective shafts 56 and 62 so that the hooks assume the position as shown in Figure 1 for the reception of the loops, and the disk 103 and rod 100 providing a means whereby it is impossible to start the machine until the notch 102 engages the rod 100 showing thereby that the parts are in the proper position for receiving the loops and for the starting operation of the present machine.

At the same time that the rod 91 was moved to the left and locked by the latch 119, the pin 93' was moved also to operate the bell-

crank lever 93 which, in turn, engaged the pin 158 and oscillated the rod 159 journaled in bearings 160. This movement caused the member 160' to be moved backward and engaged by the spring-actuated latch 161, thus holding the rod 159 in the position as illustrated in Figure 1, so that the pawl 162 carried by the rod and having the limiting pin 163 is held out of engagement with the ratchet 164, which, in turn, is mounted upon the shaft 165 at right angles to the rod 159 and journaled in bearings 166. This shaft 165 is rotated from the shaft 28 through means of the spur gears 167 and 168, the purpose of this being to provide a slowing-down of the movement of the rod 159 toward its normal position after release of the latch 119 at the final forming of the loops and previous to the starting of the spiral-forming operation.

As it is desirable that the loops be laid longitudinally of the hooks 60 and 64 instead of being piled one upon the other, the shaft 67 has slight longitudinal movement imparted thereto during the rotation thereof, this being accomplished through the medium of the rock shaft 137' carrying the yoke 138 which engages and operates the spool 69 and through the mechanism as particularly illustrated in Figures 2 and 3, Figure 2 illustrating the position it assumes when this action is taking place. The shaft 124 which, as illustrated in Figure 1, is operably connected through its gear 123 to the gear 122 and, therefore, receives motion from the shaft 15, operates the heart-shaped cam 125 and this cam in its rotation actuates the roller 126 carried by the right-angled arm 127 upon the sliding rod 128, said rod being journaled in the bearing 129 and carrying thereon the adjusting nut or member 130 for the spring 131, this spring normally holding the roller 126 into engagement with the cam 125. Upon the other end of the rod 128 is mounted an abutting member 132 which, in turn, as will presently appear, forms the connecting link between the rods 128 and 133, this rod 133 being mounted in the bearings 134 and normally held toward the rod 128 by means of the adjusting nut or member 135 and the spring 136, and being connected at its opposite end to the lever or arm 137 which rocks the shaft 137'.

Connected upon the opposite end of the rod 133 by means of the coupling 139 is the pivoted arm or connecting member 140, this member being adapted to normally assume the position as shown in Figure 2, so that when the cam is actuated, the rods 128 and 133 will be moved against the action of the two springs 131 and 136 so as to oscillate the shaft 137' and thus, in turn, oscillate the shaft 67 and cause the member 70 to move from the dotted to full line position, as illustrated in Figure 2, and vice versa. When the rod 145

was actuated, by its spring 148, as later to be described, at the end of the loop-forming operation, its pin 144 operated the lever 143 and through the shaft 141 caused the arm 142 to elevate the pivoted member 140 from the position as shown in Figure 2 to that shown in Figure 3, and thus disconnect the rods 128 and 133 so that the continued movement of the cam 125 would only oscillate the rod 128 without transmitting motion to the rod 133, and due to the spring 136 the member 69 was moved and held in the extreme left position with the member 70 in the position to be rotated slowly to feed the cord or thread to form the spirals, as will presently appear.

Spiral-forming mechanism.

As the above-described mechanism leads us up to the step at which the shaft 49 is rotated, and thus the loop carried by the hooks 60, 64 and 65 is also rotated, we now move on to the formation of the spirals S, as shown in Figure 10, and the hank as completed in Figure 11.

As the rod 73 has released the clutch member so that the member 48' is engaged, the shaft 49 is now rotated, and, in turn, rotates the change or limiting gear 104 mounted upon the shaft 105 which is disposed in the journals 106. Upon one portion of this shaft is a disk 108 and a weight-actuated arm 109, said arm being in the path to actuate and release the catch 110 from its finger 111, and thus consequently release the rod 85 to its spring action, so that the same will have moved from the position as shown in Figure 1 to the right and cause the pin 84 to engage the free end 83 of the lever 80, throwing the clutch 51 out of engagement so that the catch 77 will lock the same in the position as shown in Figure 1 and ready for the next operation. The gears 104 are so arranged and timed that a certain number of rotations are imparted to the hooks 60 and therefore, a certain number of spirals are formed around the loops to complete the hank before the machine is automatically stopped. At the same time that the rod 85 was moved by its spring 113 when released, the belt 26 was shifted from the fast pulley 27 to the loose pulley 27' and consequently the shaft 28 brought to a halt, so that the belt 31 was also halted and the slow speed driving mechanism of the shaft 15 was brought to a halt. Before this, the rod 91 was moved to the right by the spring 96 when the rod 91 was released and before the release of the rod 85.

After the slow motion was imparted through the belt 31, the cord or thread-guiding arm 70 was slowed down in its speed and during the forming of the spirals which followed slowly moved at a uniform speed longitudinally of the space between the loops 60 and 64, this being accomplished through the

mechanism as illustrated in Figures 4, 5, 6 65 and 7.

Just before the beginning of the spiral formation, the rod 145 is acted upon to cause its end 149 to be moved in the path of the latch 155, so that the latch is pushed out of contact with the projection 157 to permit the spring 156' to pull the carriage 156 downwardly or toward the pivot point of the member 70, bringing the spindle carrier 70^b into contact with the surface of the stationary cam 71 at the point X, as shown in Figure 7. This movement not only changes the position of the spindle 72 but obviously because of the pin 72^a extending through the inclined slots of the delivery spindle 72 will be caused to recede from the loop which it has been forming on the hooks and will follow the shorter path between said hooks. The arm 70 continues to revolve slowly so that the spindle carrier 70^b is moved from the position X to the position Y, at which point the spindle carrier 70^b comes in contact with an adjustable or swingingly-operated arm 151 normally held by the spring 151' against the pin 151^a and being seated within the recess 152 thereof, and due to this arm 151 is caused to follow the lines of the short arm as viewed in Figure 7 and be released as there shown upon the curved line 154, this being at the location Z. The member 150' is slotted and operably connected to the curved end of the arm 150, the same being adjustable so that its outer end may be regulated to be contacted by the spindle carrier 70^b at any point desired upon the surface of the cam 71 to, in turn, oscillate the arm 73 heretofore described for releasing the catch 77.

The spindle carrier 70^b in its slow sliding movement upon the cam thus actuates the member 150, moving it to the right, causing the bottom end of the lever 150 to move in such a direction, as before stated, to slide the rod 73 and actuate the bell-crank lever 77 and permit the clutch 51 to engage its member 48'.

The mechanism for oscillating the arm 143 against the action of its spring 148 consists of the shaft 141 which, in turn, is oscillated through the arm 169 and the rod 159, the arm 143 provided with the pin 144 being positioned to engage the rod 145, and permit the same to actuate when the catch 161 has been released by the pin 94 in its movement from left to right, as viewed in Figure 1, disengaging the catch 161, and thus releasing the shaft 159 to the action of the spring 148, which rotates the shaft 141 and thus places the pawl 163 in engagement with the ratchet wheel 164, which shaft rotates in the direction of the arrow, as illustrated in Figure 1, and thus retards the action of spring 148 on the shaft 141 so that after shaft 15 is released from its high speed control, it will have ample time to come within the slow speed

control before the member 149 on the end of rod 145 will be advanced into the circular path of the latch 155 and trip said latch.

Operation.

- 5 From the foregoing description, taken in connection with the drawings, the operation of the present machine is understood, but, briefly stated, it is as follows:—
- 10 The cord or thread A has one end made fast, as, for instance, to the hook 60, said hooks 60, 64 and 65 being in the position as shown in Figure 1 with the rod 100 locking the disk 103. The handle 87 is now moved 15 to the left to cause the oscillation of the shaft 86 and the consequent movement of the rods 85 and 91 which thus places the belts 13 and 26 so that the two shafts 28 and 15 are rotated simultaneously. At the same time that the 20 rod 91 was moved to the left, the latch 119 was engaged by the finger 121 and the rod thus held against the tension of the spring 96. Simultaneously with this, the rod 85 was moved to the left so that its latch 110 was 25 engaged by the finger 111, this rod being held against the action of the spring 113. The shaft 56 and also the shaft 49 are now stationary, while the shafts 28 and 15 are rotated, but inasmuch as the shaft 28 rotates 30 the shaft 15 through the slow speed mechanism, and as the belt 13 rotates the shaft 15 at a high speed, these mechanisms do not interfere and can be operated simultaneously. The shaft 22, as before stated, then rotates the 35 arm 70 and causes the loops to be laid and formed upon and between the hooks 60 and 64, and after a predetermined number have been laid, the shaft 115 is operated so as to release the latch 119, and, consequently, the 40 rod 91 to the action of the spring 96, which, in turn, oscillates the shaft 86 and releases the disk 103. Simultaneously with this, the latch 161 is released and the ratchet wheel 164 acts as a retarding means, or, rather, 45 transmits a retarding motion to the shaft 145, so that there is a gradual let-down in its speed at this point between the finishing of the loop and its starting of the spirals. As before stated, the spindle 72 is then moved 50 slowly from the left to the right, as viewed in Figure 1, while the loop-carrying hooks 60, 64 and 65 are rotated at a rapid speed due to the clutch 51 being released by the catch 77 and the engagement thereof with the member 55 48¹. Thus the belt 47 rotates the shaft 49 and the hooks 60, 64 and 65 until a predetermined number of spirals are formed, at which time, the change speed mechanism including the gear 104 is brought into operation to release the latch 110 and the consequent release of the rod 85 to its spring 113, which, in turn, causes the pin 84 to engage the clutch-throwing lever 80 to move the clutch 51 out 60 of engagement with the clutch member 48¹ and against the spring 52, so that the end 65

80¹ of said lever is engaged by the catch 77 and thus locked with the clutch member disengaged, or as illustrated in Figure 1.

It is apparent from the foregoing description that although only one loop-forming 70 and spiral-forming mechanism is here shown, any number may be added by the extension of the shafts 15, 49, 137¹ and 141 and by duplication of the gears 20, 53 and 54 and what they drive, and by duplication of the member 138 and the arm 143 and what they 75 actuate.

It is also apparent that the construction as illustrated is more or less diagrammatic, the same being spread out, as viewed in Figure 1, for, in the complete machine, when constructed, the rods and shafts are so closely allied as to be almost indiscernible when drawn.

It will thus be seen that by the use of the 85 cam 71, the feeder spindle 72 is moved in an orbit which is substantially elliptical when the same is operating to feed the thread to form the spirals, and that due to this orbit, the spirals or coils are uniformly laid side 90 by side throughout the length thereof; and that when the feeder spindle is in its extreme outward position that it travels in a circular orbit and thus has a larger radius in laying the loops upon the hooks 60 and 64. 95

It will also be noted that ample time must elapse between placing of the final long loop on the hooks, and laying the short loop around the hook 65 at the beginning of the spiral winding, that is, ample time for the revolving feeder 70 to recover from the centrifugal force due to the high speed at which it revolves during the laying of the loops before the end 149 slides into the path of the 100 latch 155, tripping said latch and permitting the spindle carrier 70^b to move inwardly to the surface of the cam 71 and actuate the lever 150, which starts the revolving of the hooks 60, 64 and 65. To insure this lapse of 105 time, the ratchet gear catches the pawl 162 and its rod 159 and thus lets them move slowly to the front, thus retarding and delaying the movement of the end 149 into the path of the latch 155. 110

I claim:—

1. In a hank-forming machine, a drive shaft, a rotary feeder for the thread, a pair of rotary loop-receiving means, means for rotating the feeder to lap the loops on the receiving means when the latter is stationary, 120 means for rotating the loop-receiving means, and means for rotating the feeder at a slower speed when the loop-receiving means is rotating and the thread is being coiled upon the loops, all of the said means being operably connected for sequential operation from the drive shaft. 125

2. In a hank-forming machine, a drive shaft, a rotary feeder for the thread, selective means operably connected to the drive 130

shaft and the feeder for rotating the feeder to form loops, means for rotating the feeder at a slower speed when feeding to form coils upon the loops, rotary loop-receiving means which when stationary receives the thread to form loops, selective means for operably connecting the loop-receiving means to the drive shaft to rotate the same when the thread feeder is rotated at the slower speed, and means for halting the rotary feeder and the loop-receiving means when a predetermined number of coils are formed.

3. In a hank-forming machine, a drive shaft, a rotary feeder for the thread, selective means operably connected to the drive shaft and the feeder for rotating the feeder to form loops, means for rotating the feeder at a slower speed when feeding to form coils upon the loops, rotary loop-receiving means which when stationary receives the thread to form loops, selective means for operably connecting the loop-receiving means to the drive shaft to rotate the same when the thread feeder is rotated at the slower speed, and automatic means for halting the rotary feeder and the loop-receiving means when a predetermined number of coils are formed.

4. In a hank-forming machine, a drive shaft, a rotary feeder for the thread, selective means operably connected to the drive shaft and the feeder for rotating the feeder to form loops, means for rotating the feeder at a slower speed when feeding to form coils upon the loops, rotary loop-receiving means which when stationary receives the thread to form loops, selective means for operably connecting the loop-receiving means to the drive shaft to rotate the same when the thread feeder is rotated at the slower speed, means for halting the rotary feeder and the loop-receiving means when a predetermined number of coils are formed, and means for connecting the thread receiver to the drive shaft for rotary movement when a predetermined number of loops have been laid on the loop-receiving means.

5. In a hank-forming machine, a drive shaft, a rotary feeder for the thread, selective means operably connected to the drive shaft and the feeder for rotating the feeder to form loops, means for rotating the feeder at a slower speed when feeding to form coils upon the loops, rotary loop-receiving means which when stationary receives the thread to form loops, selective means for operably connecting the loop-receiving means to the drive shaft to rotate the same when the thread feeder is rotated at the slower speed, means for halting the rotary feeder and the loop-receiving means when a predetermined number of coils are formed, and automatic means for connecting the thread receiver to the drive shaft for rotary movement when a predetermined number of loops have been laid on the loop-receiving means.

6. In a hank-forming machine, a drive shaft, a rotary feeder for the thread, selective means operably connected to the drive shaft and the feeder for rotating the feeder to form loops, means for rotating the feeder at a slower speed when feeding to form coils upon the loops, rotary loop-receiving means which when stationary receives the thread to form loops, selective means for operably connecting the loop-receiving means to the drive shaft to rotate the same when the thread feeder is rotated at the slower speed, automatic means for halting the rotary feeder and the loop-receiving means when a predetermined number of coils are formed, and automatic means for connecting the thread receiver to the drive shaft for rotary movement when a predetermined number of loops have been laid on the loop-receiving means.

7. In a hank-forming machine, a drive shaft, a rotary thread feeding mechanism, a rotary loop receiver, separate operating mechanisms for each, selective means for connecting the feeding mechanisms for operation from the drive shaft, automatic means for slowing down the speed of movement of the feeding mechanism and for connecting the loop receiver to the drive shaft when a predetermined number of loops have been formed, and whereby the loop receiver is rotated to lay coils upon the loops previously formed, and automatic means for halting the operating mechanisms when a predetermined number of coils have been laid upon the loops.

8. In a hank-forming machine, a thread feeding mechanism, a loop-receiving mechanism, a drive shaft, two driven shafts, two selective means for operably connecting the two driven shafts to the drive shaft, slow-speed mechanism interposed between the driven shaft and one of the selective means for simultaneous operation with the other selective means and for driving the driven shaft at a slower speed when the other selective means is disconnected, said threading mechanism being operated from the latter driven shaft, said shaft when operated at its higher speed causing the thread-feeding mechanism to lay the loops upon the receiving mechanism, and when operated at the slower speed and also when the loop-receiving mechanism is being rotated by the drive shaft to lay coils on the loops.

9. In a hank-forming machine, a drive shaft, a main driven shaft, selective means for connecting the same to the drive shaft, an auxiliary driven shaft, selective means for connecting the auxiliary shaft to the drive shaft simultaneously with the main driven shaft, slow-speed mechanism operated by the auxiliary shaft and operably connected to the main driven shaft, automatic means for disconnecting the selective means for directly driving the driven shaft from the drive shaft and for permitting the slow-speed mechanism

to operate the main driven shaft, a thread-feeding mechanism operably connected to the main driven shaft, loop-receiving mechanism disposed to receive the loops from the threading mechanism, the same being stationary when the loops are being formed, and automatic means for operably connecting the latter to the drive shaft and previously disconnecting the main driven shaft from the high-speed mechanism to the low-speed mechanism whereby the thread-feeding mechanism is moved at a slower speed during the rotation of the loop-receiving mechanism and the laying of the coils therefrom about the loops.

10. In a hank-forming machine, a drive shaft, a main driven shaft, selective means for connecting the same to the drive shaft, an auxiliary driven shaft, selective means for connecting the auxiliary shaft to the drive shaft simultaneously with the main driven shaft, slow-speed mechanism operated by the auxiliary shaft and operably connected to the main driven shaft, automatic means for disconnecting the selective means for directly driving the driven shaft from the drive shaft and for permitting the slow-speed mechanism to operate the main driven shaft, a thread-feeding mechanism operably connected to the main driven shaft, loop-receiving mechanism disposed to receive the loops from the feeding mechanism, the same being stationary when the loops are being formed, automatic means for operably connecting the loop-receiving mechanism to the drive shaft after disconnecting the main driven shaft from the high-speed mechanism to the low-speed mechanism whereby the thread-feeding mechanism is moved at a slower speed during the rotation of the loop-receiving mechanism and coils are laid upon the loops, and manually actuated and automatically released means for starting and stopping the operation of the mechanism, the stopping mechanism being automatically controlled when a predetermined number of coils have been formed upon the loops.

11. In a hank-forming machine, a drive shaft, three driven shafts, means for operably connecting two of the driven shafts with the drive shafts, manually controlled means for actuating the same in one direction, means for locking the operably connecting means in such selected position, a loop-receiving mechanism, means actuated by the selected means for normally holding the same in fixed position during the loop-receiving operation, thread-feeding mechanism operably connected through one of the driven mechanisms to the drive shaft and rotated at a high rate of speed for feeding the thread to the receiving mechanism to form the loops, automatic means controlled thereby after a predetermined number of loops have been formed

for connecting the feeding means to the second driven mechanism and whereby the first driven mechanism is driven at a slower speed to lay coils upon the formed loops, and automatically connected means for rotating the loop-receiving mechanism simultaneously with the shifting from the high speed to the low speed in the threading mechanism at the beginning of and during the laying of the coils, the same being operably connected to the drive shaft.

12. In a hank-forming machine, a drive shaft, three driven shafts, means for operably connecting two of the driven shafts with the drive shafts, manually controlled means for actuating the same in one direction, means for locking the operably connecting means in such selected position, a loop-receiving mechanism, means actuated by the selected means for normally holding the same in fixed position during the loop-receiving operation, thread-feeding mechanism operably connected through one of the driven mechanisms to the drive shaft and rotated at a high rate of speed for feeding the thread to the receiving mechanism to form the loops, automatic means controlled thereby after a predetermined number of loops have been formed for connecting the feeding means to the second driven mechanism and whereby the first driven mechanism is driven at a slower speed to lay coils upon the formed loops, automatically connected means for rotating the loop-receiving mechanism substantially simultaneously with the shifting from the high speed to the low speed in the threading mechanism during the laying of the coils, the same being operably connected to the drive shaft, and automatic means controlled by the rotating means actuated after a predetermined number of coils have been laid on the loops to bring the machine to a halt.

13. In a hank-forming machine, a drive shaft, three driven shafts, means for operably connecting two of the driven shafts with the drive shafts, manually controlled means for actuating the same in one direction, means for locking the operably connecting means in such selected position, a loop-receiving mechanism, means actuated by the selected means for normally holding the same in fixed position during the loop-receiving operation, thread-feeding mechanism operably connected through one of the driven shafts to the drive shaft and rotated at a high rate of speed for feeding the thread to the loop-receiving mechanism to form the loops, automatic means controlled thereby after a predetermined number of loops have been formed for connecting the feeding means to the second driven mechanism and whereby the first driven mechanism is driven at a slower speed, automatically connected means for rotating the loop-receiving mechanism substantially

simultaneously with the shifting from the high speed to the lower speed in the feeding mechanism during the laying of the coils, the same being operably connected to the drive shaft, and means operated in synchrony with the rapid rotation of the thread-feeding means for imparting a longitudinal movement to said thread-feeding means during the laying of the strands upon the loop-receiving mechanism.

14. In a hank-forming machine, a drive shaft, a main driven shaft, an auxiliary driven shaft, and a third driven shaft, selective means for connecting the main and the auxiliary driven shaft to the drive shaft for simultaneously rotation, intermediate mechanism connected between both the said shafts whereby the auxiliary driven shaft operates the main driven shaft at a reduced speed, thread-feeding mechanism operably connected to the main driven shaft, loop-receiving mechanism disposed in cooperative relation with the feeding mechanism and normally held stationary when the main driven shaft is rotated at the higher rate of speed, automatic means for disconnecting the main driven shaft from the driving shaft and permitting the auxiliary driven shaft to drive the same through the slow speed mechanism after a predetermined number of loops are formed, and automatic means controlled simultaneously therewith for operably connecting the third driven shaft to rotate the loop-receiving mechanism simultaneously with the formation of the coils and the feeding of the thread from the slow moving thread-feeding mechanism.

15. In a hank-forming machine, a drive shaft, a main driven shaft, an auxiliary driven shaft, and a third driven shaft, selective means for connecting the main and the auxiliary driven shaft to the drive shaft for simultaneous rotation, intermediate mechanism connected between both the said shafts whereby the auxiliary driven shaft operates the main driven shaft at a reduced speed, thread-feeding mechanism operably connected to the main driven shaft, loop-receiving mechanism disposed in cooperative relation with the feeding mechanism and normally held stationary when the main driven shaft is rotated at the higher rate of speed, automatic means for disconnecting the main driven shaft from the driving shaft and permitting the auxiliary driven shaft to drive the same through the slow speed mechanism after a predetermined number of loops are formed, automatic means controlled simultaneously therewith for operably connecting the third driven shaft to rotate the loop-receiving mechanism simultaneously with the formation of the coils and the feeding of the thread from the slow moving thread-feeding mechanism, and automatic means for disconnecting the auxiliary driven shaft and the third driven

shaft from the drive shaft after a predetermined number of coils have been wound around the loops to form the hank.

16. In a hank-forming machine, a driven shaft, a main driven shaft, an auxiliary driven shaft, and a third driven shaft, selective means for connecting the main and the auxiliary driven shaft to the drive shaft for simultaneous rotation, intermediate mechanism connected between both the said shafts whereby the auxiliary driven shaft operates the main driven shaft at a reduced speed, thread-feeding mechanism operably connected to the main driven shaft, loop-receiving mechanism disposed in cooperative relation with the feeding mechanism and normally held stationary when the main driven shaft is rotated at the higher rate of speed, means operated simultaneously with the rotation of the feeding mechanism for imparting longitudinal movement thereto to determine the positioning of the loops in the loop-receiving mechanism, automatic means for disconnecting the main driven shaft from the driving shaft and permitting the auxiliary driven shaft to drive the feeding mechanism through the slow speed mechanism after a predetermined number of loops are formed, and automatic means controlled simultaneously therewith for operably connecting the third driven shaft to rotate the loop-receiving mechanism simultaneously with the formation of the coils and the feeding of the thread from the slow moving thread-feeding mechanism.

17. In a hank-forming machine, a drive shaft, a rotary feeder for the thread, two outer rotary loop receivers upon which when stationary are wrapped all of the full loops of the hank, an intermediate loop receiver attached to one of the outer loop receivers and located in a line between the other two loop receivers and around which a partial loop is wrapped at the initial starting point of the loop unwrapping coils, means for rotating the feeder to lay the loops on the loop receivers when the loop receivers are stationary, means for simultaneously rotating all loop receivers, and means for rotating the feeder at a slower speed when the three loop receivers are rotated and after the third intermediate loop receiver has been brought into use, whereby the coils are wound about the loops and the thread is gradually guided to successively lay the coils, and all of said means being operably connected for sequential operation from the drive shaft.

18. In a hank-forming machine, the combination of means for receiving the loops to form a hank when stationary and for forming coils about the loops when rotated, a rotary thread-guiding means having a movable portion through which the thread is delivered to the loop-receiving means, and means for regulating the orbit of movement of the movable

portion of the thread-guiding means, whereby during its larger orbit movement the loops are formed and whereby during its smaller orbit movement the thread is progressively fed to 5 form the coils of the hank.

19. In a hank-forming machine, the combination with means for receiving loops and coils to form a hank, and means for feeding the thread thereto, the latter comprising a ro-

tating thread carrier, a thread guide mounted 10 in the carrier for movement in two orbits, and a cam for determining the inner orbit and consequently the formation of the loops and the coils of the hank.

In testimony whereof I have hereunto set 15 my hand.

JOHN F. SCHENCK, Sr.
